(57) **CLAIM**

The ornamental design for a modular video support frame member, as shown and described.

DESCRIPTION

FIG. 1 is a front perspective view of a modular video support frame member, the modular video support frame member having a plurality of mounting flanges shown in a first position;

FIG. 2 is a rear perspective view thereof;

FIG. 3 is a front view thereof;

FIG. 4 is a top view thereof, the bottom view is a mirror image of the top view;

FIG. 5 is a right side view thereof, the left side view is a mirror image of the right side view;

FIG. 6 is a rear view thereof;

FIG. 7 is an enlarged view of a portion of FIG. 3;

FIG. 8 is a rear view thereof;

FIG. 9 is an enlarged view of a portion of FIG. 3 showing a mounting flange in a second position;

FIG. 10 is a rear view thereof;

FIG. 11 is an enlarged view of a portion of FIG. 1;

FIG. 12 is an enlarged view of a portion of FIG. 2;

FIG. 13 is a front perspective view of another embodiment of a modular video support frame member, the modular video support frame member having a plurality of mounting flanges shown in a first position;

FIG. 14 is a front view thereof;

FIG. 15 is a top view thereof, the bottom view is a mirror image of the top view;

FIG. 16 is a right side view thereof, the left side view is a mirror image of the right side view;

FIG. 17 is a rear view thereof;

FIG. 18 is an enlarged view of a portion of FIG. 14;

FIG. 19 is an enlarged view of a portion of FIG. 14 showing a mounting flange in a second position; and,

FIG. 20 is an enlarged view of a portion of FIG. 13.

The broken lines in the Figures are for the purpose of illustrating unclaimed portions of the modular video support frame member and form no part of the claimed design.

The shade lines in the Figures show contour and not surface ornamentation.

1 Claim, 18 Drawing Sheets
